UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

APPARATUS FOR DEFLATING TUBES.

Application filed June 7, 1922. Serial No. 566,443.

My invention relates to apparatus for use in deflating collapsible tubes, particularly pneumatic tire tubes, although it may be utilized in various other capacities as will hereinafter appear.

In manufacturing tubes, for pneumatic tires, it is the usual practice to subject them to a test, while they are inflated with air, in order that leaks and other imperfections 5 may be detected. Obviously, in order that tubes so tested, and, in fact, tubes that have not been so inflated and tested, must have the air exhausted from them before they can be compactly folded for storage and 10 shipment. Various expedients have heretofore been resorted to for accomplishing this 15 result, each of which while possessing certain advantages, is susceptible of improvement as will be recognized by those familiar 20 with such practices and the present forms of apparatus that are available for such purposes.

The purpose of the present invention, broadly stated, is to provide a more practical 25 and simplified form of apparatus than has heretofore been available, which may be utilized to exhaust the air from tire tubes during their manufacture, either those that have been inflated or those that have not 30 been subjected to an inflation pressure, and which will leave the tubes in satisfactory condition for packing in tube boxes.

The invention is also directed toward providing a type of apparatus whereby a number 35 of tubes may be treated in a single operation to simultaneously exhaust the air therefrom, and which may be easily operated by a single attendant.

Another object of the invention is to provide 40 an apparatus of the character, and for the purpose above stated, whereby the tubes may be treated without danger of their becoming mutilated either by the operation of the apparatus or by carelessness on the 45 part of the operator.

Other objects and advantages, such as relatively low cost of manufacture, dependability in operation, and the provision of an apparatus which will relieve the operator 50 of the labor heretofore necessary for the preparation of tubes for packing, will appear when the following description is read in conjunction with the drawings accompanying and forming a part of this specification.

In the drawings:

Figure 1 is a side elevation of a tube deflating apparatus constructed in accordance with my invention, and illustrating the parts of the apparatus in their normal or starting 60 position;

Figure 2 is a similar view, on a reduced scale, illustrating the operation of the invention;

Figure 3 is a front elevation of the apparatus;

Figure 4 is a sectional view of a detail of the invention; and

Figure 5 is a sectional view of another detail of the invention.

Referring to the drawings, wherein there is illustrated a preferred form of apparatus constructed in accordance with my invention, 1 indicates a vertical standard which may be secured in an upright position upon any suitable form of base, such, for instance, as that designated by the numeral 2. The standard 1 is designed to support a plurality of tubes in suspended position and in side by side relation to be simultaneously engaged by a presser member 3, presently described, so that the tubes are compressed between the standard and said member. To this end the standard is of greater height 75 than the length of the larger sizes of tubes, 80 when they are in the position above indicated, and the tubes are suspended from a point adjacent the top of the standard. As a preferred means of properly suspending the tubes, a bracket 4 is provided upon the upper portion of the rear face of the standard 1, the bracket comprising a vertical arm 5 that is suitably secured centrally of the standard, and a forwardly projecting arm 6 in which there is mounted an adjustable 85 horizontal bar 7. The bar 7 is adjustably mounted in the arm 6 so that it may be arranged to extend an equal distance upon each side of the bracket 4, and the bracket 90 is so constructed that the bar is positioned 95 slightly in advance and a short distance above the front face of the standard 1. The bracket is so arranged that a plurality of tubes, indicated at 8, may be suspended from the bar 7, in the manner illustrated in the drawings, with the valve stems 9 in substantially the position shown relative to the bar and the standard 1, although the double construction is not essential. Preferably I 100 utilize any one of the well known forms of

100

105

110

cap devices, not shown, for holding the valve mechanism open, or I may remove the mechanism of the valve from within the stem.

The presser member 3 is substantially co-extensive in length with that of the standard 1 and is hinged at its lower end to the standard, as at 10. It is pivoted at the end remote from the valve stem location and is movable relative to the standard 1 and to be moved thereagainst to compress the tubes between its rear face and the front face of said standard; the apparatus thus expelling the air upwardly toward the valve stem. In order to retain the member 3 in its open position, a bracket 11 is secured adjacent its lower end, the bracket in this instance comprising downwardly extending arms 12 projecting beyond each edge of the member and terminating below the hinges 10 thereof.

Upon each side of the base 2, retractile springs 13 are provided, one end of each spring being attached to the base while the other end thereof is attached to the lower end of one of the arms 12.

As a means of moving the presser member 3 toward the standard 1, I provide the following devices:

Upon the rear face of the standard a pair of spaced brackets are mounted, between which the forward end of a fluid pressure cylinder 14 is secured for oscillation about a horizontal axis extending transversely of the standard 1. The cylinder may be of any suitable construction, but preferably comprises a head member 15 which, in this instance, is provided with pintles, one of which is shown at 16. The pintles are journaled in the brackets, one of which is shown at 17. At its forward end the cylinder is provided with a combined inlet and outlet pipe 18 which carries two valves, designated respectively 19 and 20. Valve 19 is of any well known type which may be set to admit fluid pressure to any given degree, so that only a predetermined pressure may be admitted to the cylinder 14. Valve 20 is the operating valve and is adapted to admit fluid under pressure from a main line indicated at 22 through valve 19 and is provided with a vent 23 with which it may be registered to exhaust the fluid medium from the cylinder 14 while cutting off the supply from said main line. The cylinder is provided with any suitable form of piston 24 and rod 25, the arrangement of the piston in the cylinder 14 being such that when fluid under pressure is admitted to the cylinder through the aforesaid valves, it will be moved toward the rear of the cylinder. The rod 25 passes through a suitable opening 26 in the standard 1, and through a similar opening 27 in the member 3. At its forward end the rod is pivotally connected, in any suitable manner, to the member 3, for instance as indicated at 28.

The operation of my invention, it is believed, will be apparent from the foregoing description and therefore will not be described in detail. Briefly, it is as follows:

The operator or attendant, after placing a plurality of tubes upon the bar in the position and manner previously described, adjusts the valve 19 to the proper pressure point regulated by the size of the tube on which he is operating. The valve 20 is then opened to admit fluid under pressure from the main line 22 to the forward end of the cylinder 14, whereupon the active member 3 is moved against the standard 1 which serves to expel the air from the tube, from the lowermost portion of the tube to the valve stem, and squeezes the tube into flat condition so that it is in better shape for packing than has been done by prior types of apparatus. The operator may utilize the valve 19 in conjunction with the valve 20, to exhaust the fluid from the cylinder 14 if it is desired to utilize only a certain pressure therein, whereby mutilation of the tubes may be positively prevented. When the air is exhausted from the cylinder, the springs 13 return the member 3 and the piston 24 to starting position. During the deflating operation and the return movement of the parts of the apparatus to starting position, the cylinder 14 is free to oscillate in the brackets 17 as the member 3 oscillates upon its hinges 10. Likewise the rod 25 and piston 24 are free to adjust themselves by virtue of the pivotal connection 27 of the rod.

Although I have described my invention in detail and therefore utilized certain specific terms and language herein, it is to be understood that the present disclosure is illustrative, rather than restrictive, and that changes and modifications may be resorted to without departing from the spirit or the scope of the claims appended hereto.

What I claim is:

1. Apparatus for exhausting air from collapsible tubes comprising, cooperating presser members operable to receive and compress the tubes therebetween, means for suspending the tubes between said members, and means for operating said members.

2. Apparatus for exhausting air from collapsible tubes comprising, cooperating presser members normally arranged in spaced relation to receive a plurality of tubes therebetween, means for operating said members to compress the tubes, and means for regulating the degree of compression effected upon the tubes by said members.

3. Apparatus for exhausting air from collapsible tubes comprising, opposed presser members adapted to receive and compress a plurality of tubes therebetween, one of said members being movable relative to

the other, pressure actuated means for moving said first member, and means operable to control said pressure actuated means.

4. Apparatus for exhausting air from collapsible tubes comprising, opposed presser members normally arranged in spaced relation to receive a tube therebetween one of said members being movable to compress the tube against the other member, means for supporting the tube between said members with the valve stem outside of the presser members, and means for moving said first means.

5. Apparatus for exhausting air from collapsible tubes comprising, opposed presser members normally arranged in spaced relation to receive a plurality of tubes therebetween one of said members being movable relative to the other to compress the tubes therebetween, means upon one member for supporting the tubes with the valve stems exposed, and means for moving the members relatively to one another.

6. Apparatus for exhausting air from collapsible tubes comprising, a vertically disposed presser member, an oscillatable presser member, a support upon one member for suspending a plurality of tubes in parallel relation, means for yieldingly retaining the second member in spaced relation with respect to the first member, and pressure actuated means for moving the second member toward the first member.

7. Apparatus for exhausting air from a collapsible tube comprising, cooperating

members adapted for receiving a tube therebetween, means for holding said tube in suspended position, one of said members being operable to compress the tube against the member, and means for operating said first member.

8. Apparatus for exhausting air from a collapsible tube comprising, cooperating members adapted for compressing a tube, means for holding said tube in suspended position, one of said members being movable relative to another member, means for moving said first member, and means for controlling the degree of compression exerted against the tube.

9. In an apparatus for removing air from an inner tube, means for supporting the inflated tube, and means embracing the tube in such condition for expelling the air therefrom.

10. In an apparatus for removing air from an inner tube, means for supporting the inflated tube suspended in elongated condition and with the valve stem exposed, and means embracing the tube progressively toward the valve to expel the air from the tube.

11. In an apparatus for removing air from an inner tube comprising, means for supporting the inflated tube suspended in elongated condition and with the valve stem exposed, and means to embrace said tube and flatten the same.

HORACE D. STEVENS.
